UNITED STATES PATENT OFFICE.

CLAES RYDEN, OF PROVIDENCE, RHODE ISLAND, ASSIGNOR TO UNIVERSAL WINDING COMPANY, OF PORTLAND, MAINE, A CORPORATION OF MAINE.

TENSION DEVICE.

1,048,889.

Specification of Letters Patent.

Patented Dec. 31, 1912.

Application filed March 25, 1912. Serial No. 685,964.

To all whom it may concern:

Be it known that I, CLAES RYDEN, a citizen of the United States, residing at Providence, in the county of Providence and State of Rhode Island, have invented certain new and useful Improvements in Tension Devices, of which the following is a specification.

My invention relates to tension-devices and consists of an improved means for applying tension to yarn, thread or twine delivering from cops, bobbins or other supply packages.

The object of my improvement is to provide a device which will restrain the yarn from flying out or "ballooning" as it unwinds from the bobbin or other supply, thereby giving greater uniformity of tension and preventing kinking or snarling of the yarn.

The invention is fully described in the following specification, illustrated by the accompanying drawings, in which:—

Figure 1 is a view showing a usual form 25 of bobbin having my new device applied thereto; Fig. 2, a view of a part of the device shown in detail; Fig. 3, a view showing a modification in the form of the invention, and illustrating a different method of drawing the yarn off from the bobbin.

My new device is particularly adapted for use with cops or bobbins which are wound with superimposed conical layers progressing along the central tube or holder 35 to form a cylindrical body portion terminating in a tapered delivery end or "nose" from which the yarn unwinds.

In Fig. 1 I have illustrated a bobbin B of this form adapted for use particularly 40 with knitting machines, or for any other purpose where it is required to deliver yarn in the various processes of manufacture. The bobbin is usually wound on a holder or support b which is generally formed with 45 a tapering base b' and a tubular barrel or shank b² extending therefrom. In delivering the yarn from the bobbin the latter is preferably set upon a base-plate or standard S, which has attached thereto an upright 50 arm s, bent at s' to extend over the center of the bobbin, and supporting an eye or guide g through which the yarn y draws.

My new tension-device in its preferred embodiment consists essentially of a bush-

room-shaped cap C having a plug c adapted 55 to fit the bore in the end of the holder b and provided with an upwardly-extending projection or stud c' on which a ring D is loosely mounted. The head of the cap C is preferably a little larger in diameter than 60 the barrel b² of the bobbin-holder b, and is formed with its lower edge slightly rounded off and curving into the full convex surface on top. The upwardly-extending projection c' is also rounded or semi-spherical on top 65 so that all the parts present smooth surfaces to the yarn which draws across them.

The ring D is preferably cylindrical in cross-section and is of sufficient diameter to adapt it to fit over the projection or stud 70 c' with a slight clearance between the two. Normally, the ring D rests on the main portion or head of the cap C and the yarn y is drawn up through the ring as illustrated in Fig. 1. The device may be threaded by 75 removing the ring D from the cap and leading the yarn through it, after which the ring is replaced on the stud c'; but to provide for greater convenience in threading, I prefer to construct the ring D with a slit or opening 80 d through which the yarn can be inserted into the ring without the necessity of leading its end through. Referring to Fig. 2, the slit d is cut through the ring on an angle, instead of radially, so as to prevent 85 the yarn from drawing out through the slit as it slides around the ring as hereinafter more fully explained.

The operation of the device above described is as follows: The cap C is placed on 90 top of the bobbin and the yarn y led up under and through the ring D as shown in Fig. 1. From the ring D the yarn leads up through the guide g, and thence to the machine in which it is to be used. As the yarn 95 is taken up by the machine it unwinds from the bobbin and draws up over the rounded face of the cap C and between the ring D and the projection c'. The resistance to the unwinding of the yarn at the bobbin causes it 100 to travel around the cap and this sets up a slight friction which is augmented by the action of the ring D. That is to say, the ring D holds the yarn against the stud c' and in this way a light, delicate tension is 105 applied. The amount of tension can be varied as required by using heavier or lighter rings. Referring again to Fig. 2,

the arrow α indicates the direction of travel of the yarn around the ring D, and it will be noted that owing to the angular arrangement of the slit d there will be no possibility 5 of the yarn pulling out through the slit. Furthermore, the yarn will not meet with any obstruction from the slit d in its passage around the ring D, as it will slide off of the sharp point d' of the slit onto the 10 smooth edge d'.

Fig. 3 shows a modification of the invention and illustrates another method of drawing off the yarn from the bobbin. In some cases it is desirable to lead the yarn off 15 from the base of the bobbin and this is accomplished by arranging the device in the following manner: The cap C' is constructed with an axial opening c² extending down through the plug c, and at the top of 20 the cap the opening has a flaring mouth adapted to receive a ball E. With this arrangement the yarn y is led up over the curved face of the cap C' and down through the opening c². The base or standard S' on 25 which the bobbin B sets has a vertical tube or upright s², and the yarn leads down through this and draws out through an opening s³ in one of the legs s⁴ of the standard. It will be understood that the standard 30 for the bobbin here shown and described forms no part of the present invention and any other suitable arrangement might be used for leading the yarn out through the base of the bobbin. After the 35 yarn has been threaded through the cap C', as described, the ball E is placed in the opening c² to impinge on the yarn and press it against the cap. As the yarn unwinds from the bobbin it circles around the 40 edge of the cap and this sets up a friction which is augmented by the weight of the ball E. In this way tension is applied to the yarn to control its delivery in practically the same manner as that previously 45 described in connection with the operation of the ring D on the cap C, the arrangement of the parts being merely inverted.

It will be observed that with my new device the tension is applied to the yarn 50 directly at the top of the bobbin so that the length of yarn extending from the bobbin to the machine is maintained taut. The yarn is therefore restrained from whipping or flying out from the bobbin and by eliminating the "ballooning" of the yarn I prevent snarling and kinking and provide for a more uniform tension. When the yarn is 55 allowed to "balloon" it meets with resistance, due to the air pressure, in unwinding 60 from the bobbin, and as the radius of the balloon is constantly fluctuating during the delivery of the yarn the tension on the yarn will fluctuate in accordance therewith. In other words, the play of the yarn away from 65 the bobbin varies under different conditions,

as, for instance, in unwinding from the small diameter and then from the larger diameter, in going from the point to the base of the nose of the bobbin, and these variations set up corresponding changes in 70 the air resistance which affect the tension on the yarn. Furthermore, when the yarn is allowed to fly out from the bobbin it has a tendency to twist and loop upon itself and these loops often cause kinking and snarling. It is obvious that when snarls or kinks occur the machine to which the yarn is delivering must be stopped and the yarn straightened out and untwisted. This results in loss of time and waste of material 75 so that the production of the machine is curtailed and the cost of the product increased. In addition, the irregularities in tension on the yarn cause defects in the fabric being manufactured, and often impair the quality of the goods so that they are fit only for "seconds."

With my improved device a smooth, even tension is applied to the yarn and the tension is maintained uniform from start to 90 finish of delivery, so that greater production of the machine is assured and defects in the fabric prevented. The yarn is prevented from kinking and snarling and, therefore, waste from this source is avoided. 95

Various modifications might be made in the structure and arrangement of the parts of my device without departing from the spirit or scope of the invention.

Therefore, without limiting myself to the 100 exact construction shown and described, what I claim is:—

1. In a tension-device for bobbins or cops, the combination with a cap adapted to be mounted on the end of the bobbin, of a ring-member resting on said cap and operated by gravity to press on the yarn as the latter draws through it and between said member and the cap.

2. In a tension-device for bobbins or cops, the combination of two members mounted one upon the other, with one member surrounding the other member and arranged with the yarn leading through it to adapt it to revolve around its interior, and one of 115 said members bearing on the yarn through the action of gravity.

3. In a tension-device for bobbins or cops, the combination with a fixed member, of a movable member resting on the fixed member, one of said members surrounding the other member with the yarn drawing through it and adapted to revolve about the other member, said members adapted to press upon the yarn through the action of gravity.

4. In a tension-device for bobbins or cops, the combination of two members, one fixed and the other movable, and one of said members formed as a ring adapted to surround the other member with the yarn drawing 130

through its opening and adapted to revolve about the other member and between it and the other member.

5. In a tension-device for bobbins or cops, the combination with a cap formed with an upwardly-projecting stud, of a ring mounted loosely on the stud to adapt the yarn to lead under and through said ring to allow it to revolve about the stud as the yarn is 10 drawn from the bobbin.

6. In a tension-device for bobbins or cops, the combination with a cap formed with a plug adapted to fit the bore of the bobbin support, of a ring-member mounted on the 15 cap to adapt the yarn to lead through the ring and to be pressed thereby against the cap.

7. In a tension-device for bobbins or cops, the combination with a cap formed with a 20 convex face and a stud projecting upwardly therefrom, of a ring mounted on said stud with a clearance between the two to adapt the yarn to lead across the cap and through the ring.

8. In a tension-device for bobbins or cops, 25 the combination with a mushroom-shaped cap formed with a plug adapted to fit the bore of the bobbin support and an upwardly-projecting stud, of a ring surrounding the stud and arranged to press the yarn against the cap as it draws through the ring.

9. In a tension-device for bobbins or cops, the combination with a fixed member of a ring loosely mounted on said member, said ring formed with a slit for the insertion of 35 the yarn into the ring.

10. In a tension-device for bobbins or cops, the combination with a fixed member, of a ring mounted on said member, said ring having a slit cut through it at an angle to the 40 diametrical plane extending across the slit.

In testimony whereof I affix my signature in presence of two witnesses.

CLAES RYDEN.
